US00D348915S

United States Patent [19]Fraser*Patent Number: Des. 348,915*Date of Patent:  Jul. 19, 1994*[54] PLAY BALL*[75] Inventor: Stanley Fraser, Mapperley, United Kingdom*[73] Assignee: S. Fraser Chemicals (Nottingham) Ltd., Nottingham, United Kingdom*[] Term: 14 Years*[21] Appl. No.: 910,595*[22] Filed: Jul. 8, 1992*[30] Foreign Application Priority Data

Jan. 11, 1992 [GB] United Kingdom 2020160

[52] U.S. Cl. D21/204

[58] Field of Search 273/58 K; D21/204, 205, D21/108, 107

[56] References CitedU.S. PATENT DOCUMENTSD. 326,937 6/1992 Miyahara D21/204
927,499 7/1909 Davis D21/107
2,521,703 9/1950 Emmitt D21/2054,919,422 4/1990 Ma 273/58 K
5,020,438 6/1991 Brown 273/58 K
5,207,420 5/1993 Crawford et al. 273/58 K*Primary Examiner—Melvin B. FeiferAttorney, Agent, or Firm—Haugen and Nikolai[57]*CLAIM

The ornamental design for a play ball, as shown and described.

DESCRIPTION

FIG. 1 is a front view of the play ball embodying my design;

FIG. 2 is a rear view of the play ball of FIG. 1;

FIG. 3 is a bottom view of the play ball of FIG. 1;

FIG. 4 is a top view of the play ball of FIG. 1;

FIG. 5 is a left side elevational view of the play ball of FIG. 1;

FIG. 6 is a right side elevational view of the play ball of FIG. 1;

FIG. 7 is a perspective view of the play ball of FIG. 1

taken from the rear and one side; and,

FIG. 8 is a perspective view of the play ball of FIG. 1

taken from the front and one side.

Fig. 1

Fig. 2

Fig. 3

Fig. 4

Fig. 5

Fig. 6

Fig. 7

Fig. 8